UNITED STATES PATENT OFFICE.

JOHN J. RITTER, OF URBANA, OHIO, ASSIGNOR TO THE W. B. MARVIN MANUFACTURING COMPANY, OF URBANA, OHIO, A CORPORATION OF OHIO.

PLANE.

Application filed January 15, 1926. Serial No. 81,415.

My invention relates to improvements in planes, it particularly relating to a small bench type of plane.

An object of my invention is to devise a plane of this character which can be simply and cheaply constructed and which will be effective in operation.

A further object of the invention is to provide an arrangement in which the frog or blade support is so formed that it can be readily attached to the body or frame of the plane and not only support the blade 1 but also form a convenient palm rest for the hand of the operator.

15 In the accompanying drawings:

Fig. 1 is a plan view.

Fig. 2 is a sectional view on the line 2—2 of Fig. 1.

20 Fig. 3 is a front elevation with the blade in place.

Fig. 4 is a front elevation with the blade removed.

Referring to the drawings, the body or stock of the tool is constructed of channel 25 form in which 1 represents the bottom and 2 the sides, each of the sides being inclined downwardly and rearwardly toward the front and rear of the body as shown in Fig. 2. This body is constructed of sheet 30 metal bent to the shape shown.

The frog or support for the knife blade 3 is also formed of sheet metal and is shaped to form a forwardly inclined portion 4 and a rearwardly inclined portion 5. The forwardly extending portion 4 has at each side thereof a downturned flange 6, which flanges are bent to lie parallel with the sides 2 and are secured, respectively, to the sides, preferably by spot welding. The rearwardly inclined portion 5 has at its rear end a lip or flange 7 which is bent so as to lie parallel with the bottom 1 and is secured thereto preferably by spot welding. The sides 5' of the rearwardly inclined portion 5 are bent 45 downwardly on a curve and the main part of this portion 5 lies above the upper edges of the sides 2 and provides a convenient rest for the palm of the hand of the operator. The forwardly projecting portion 4 is formed 50 with an aperture 8, the metal being upset and threaded to receive a screw 9 having wings 10. The blade 3 is provided with a slotted opening 11 through which the screw extends so that the knife blade may be 55 clamped in different positions of adjustment.

The bottom 1 is provided with the usual slotted opening 12 through which the edge of the blade extends.

In assembling the parts the forward end of the frog is attached to the sides 2 before 60 it is bent, as indicated in dotted lines in Fig. 2, and a fixed rod is then placed beneath the frog at the point marked 13 in Fig. 2 and the rear portion 5 bent downwardly to proper position and secured as before stated 65 by spot welding to the bottom 1. The central portion of the frog or that portion indicated at 13 is preferably weakened by cutting away the sides thereof as indicated at 13 so that the frog may be readily bent over 70 the stationary rod.

By this arrangement it will be seen that a plane is provided which may be very simply and cheaply constructed so as to be sold at a low price. Further, by the arrangement 75 of the blade support this support may not only be readily attached to the body of the tool but the rear portion thereof provides a convenient place for the operator to rest the palm of his hand in operating the tool. 80

Having thus described my invention, I claim:

1. In a plane, a channel-shaped body, a one-piece member constructed as a separate part from said body and shaped to form a 85 forward downwardly inclined portion and a rear downwardly inclined portion to provide, respectively, a blade support and a palm rest, and means for securing both portions to said body. 90

2. In a plane, a channel-shaped body having its sides rearwardly inclined, a one-piece member constructed as a separate part from said body and having a forward downwardly inclined portion and a rear downwardly inclined portion, said forward portion being secured to the sides of the body and said rear portion secured to the bottom of the body. 95

3. In a plane, a body having sides, a one-piece member constructed as a separate part 100 from the body of sheet metal bent to a substantially inverted V-form to provide a forward downwardly inclined blade support and a rear downwardly inclined palm rest, means for securing the forward part to the 105 sides of the body, and an integral part on the rear end of said palm rest bent to lie parallel with the bottom of the body and secured thereto.

4. In a plane, a channel-shaped body hav- 110

ing rearwardly inclined sides, a one-piece support bent to a substantial inverted V-shape so as to extend forwardly and rearwardly on an incline, integral lugs on the sides of the forwardly extending portion of said support and bent parallel with the sides of said body and secured thereto, and an integrally formed lug at the rear end of the rearwardly inclined portion of said support bent parallel with the bottom of said body and secured thereto.

5. In a plane, a channel-shaped sheet metal body having rearwardly inclined sides, a

sheet metal support having a forwardly extending portion and a rearwardly extending portion, said forwardly extending portion being secured to the sides of said body and said rearwardly extending portion being secured to the bottom of said body, said rearwardly inclined portion of said support being provided with rounded sides to adapt said support as a rest for the palm of the operator.

In testimony whereof, I have hereunto set my hand this 12 day of January, 1926.

JOHN J. RITTER.
